UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,151.

Specification of Letters Patent. Patented Aug. 11, 1914.

Application filed April 24, 1907. Serial No. 370,051.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and particularly to semi-automatic systems in which automatic switches or their equivalent are employed to effect inter-connection of lines as determined 15 by manual apparatus controlled through the agency of operators.

My invention has for its object the provision of a number of sets of switching apparatus sufficient for the probable needs of 20 the service, but not necessarily equal to the number of lines, and most desirably less than the number of lines; the provision of operators' controlling sets less in number than the number of lines, and the distribution of 25 the load, that is to say, the incoming calls, among the sets of switching apparatus, and among the operators, whereby uniform efficiency in service may be attained.

For the sake of simplicity in description I 30 shall specify herein automatic switches of the type known as "Strowger" selectors and connectors, the construction of such switches being well shown in Letters Patent No. 815,176 and No. 815,321, granted to Keith 35 and Erickson, March 13, 1906. The circuits commonly employed with these switches are well known to those skilled in the art. I shall also specify a type of common battery line circuits and central office talking circuits 40 which are considered standard, and generally known as two-wire bridged battery circuits. It is to be understood however that in specifying the apparatus and circuits mentioned they are used as types for purposes of description, and not as limiting the 45 invention.

Stated in terms of the embodiment thus presented, the present invention comprises a number of groups of selector and connector 50 switches less than the number of lines to be served; a number of primary selector switches normally set back to a fixed or zero position, and adapted to connect the calling lines with the said groups of selector and connector switches; a number of operators'

selective keys and impulse transmitting means controlled thereby, with automatic secondary selector switches normally set back at a zero or idle position, and acting to connect the trunks from the primary selector switches to the operator's apparatus when the calls are received, whereby the operators may connect with the calling subscribers, and may actuate the appropriate selector and connector switches to connect the calling 65 and the wanted lines.

By having all the primary and secondary selector switches normally set back to zero, I effect a uniform distribution commencing always with the first trunk or the first position. 70 When a subscriber calls in, current in his line energizes a relay which starts up his primary selector switch, said switch continuing to progress step by step until its wipers rest upon the terminals of an idle trunk, at 75 which time the cut off relay of the line receives current from the switch circuit, the switch stops, and the secondary selector switch is started to connect the trunk to an idle operator's circuit. An appropriate signaling means such as a lamp, is provided for each operator's circuit, and the operator being thus apprised of a call is able to connect her telephone through her circuit to the 80 trunk and thence to the calling line, and afterward to transmit impulses to the trunk and forward to its automatic first selector switch to secure connection with the line wanted. Testing and ringing of the wanted line are automatic.

90 The specific distinguishing feature of the invention claimed in the present case is that each line has a terminal selector switch by which it may be connected in calling to an idle trunk line leading to a first selector switch; and each operator's circuit is provided with a switch starting up from a zero or normally inoperative position to select and connect with a trunk line upon which a call is landed. This operator's switch remains connected to the trunk as long as suffices to send the proper impulses for setting the switches to complete the connection, after which it returns to zero and is ready to be started up again by another call, to 100 select the trunk thereof.

105 My invention is illustrated in the accompanying drawings in which—

Figure 1 is a diagram showing a calling subscriber's line and a portion of the central 110

office equipment. Fig. 2 is a similar diagram complementary to Fig. 1, and intended to be placed below the latter, showing another portion of the central office circuits. 5 Fig. 3 is a similar diagram also complementary to Fig. 1, intended to be placed at the right of the latter, and showing a selector and connector switch with their circuits, through which the calling line may 10 be connected with any one of a considerable number of other lines. Fig. 4 is a diagram of circuits complementary to Fig. 2, intended to be placed at the right of the latter. Fig. 5 is an end view of an improved rotary 15 selector switch. Fig. 6 is a section on the line X—X of Fig. 5. Fig. 7 is a similar view with the bank contacts removed, of a modification of the switch shown in Fig. 5. Fig. 8 is a diagram showing connections 20 between operators' sets whereby the calls are properly distributed and more than one operator's selector switch is prevented from being set into operation by a single call.

Referring to Fig. 1, A is a subscriber's 25 station connected to the central office by the line wires 1 and 2, which are normally connected through the contacts of a cut-off relay N to the line relay M and to ground, respectively, the line relay being connected 30 to the main battery through the wire 3. Line extensions 4 and 5 pass from the cut-off relay to the wipers of a step by step selector switch S, this switch being what is called a "single motion" or rotary switch, 35 having a spindle s journaled so that it can turn upon its axis, and provided with a ratchet wheel by which it may be turned. This ratchet wheel is engaged by a stop or 40 detent pawl i controlled by the electromagnet s', and a stepping or working pawl controlled by the electromagnet s". The circuit of the electromagnet s" is controlled by the line relay M through its armature m, for 45 which purpose the front contact 7 of the relay is connected by a wire 8 and interrupter I with the magnet s" while the armature m is connected with the battery wire 3. This interrupter is continuously operating and may consist, as shown, of a rotative cylinder 50 having alternate conducting and insulating portions, one conductor being connected with the conducting portion and another with a pen bearing upon the cylinder, so that as the cylinder rotates the conductors 55 will be alternately connected together and disconnected as the pen successively bears upon the conducting and insulating portions. The cylinder is continuously driven by any suitable means. With such an arrangement it is only necessary to maintain 60 the circuit closed when the successive energizations and deenergizations of the magnet and vibrations of its armature will continue indefinitely. In the present case, as the 65 magnet s" vibrates its armature, it also turns

the spindle s by means of its pawl and the ratchet on the spindle, any retrograde motion of the spindle being prevented by the fixed stop pawl controlled by the magnet s'. The spindle is provided with a return spring 70 preferably a coiled spring, which has a constant tendency to turn the spindle back against the pawl of the magnet s' and which when this pawl is released by the energization of its magnet, will actually turn back 75 the spindle into its normal, zero or inoperative position. The mechanical construction suitable for a switch S as described will be set forth hereinafter. The line relay M also 80 partially controls the circuit of the release magnet s'. For this purpose the armature m is connected to the main battery wire 3 through the branch 6. The circuit of this release magnet is normally open at the springs a' and b', which are worked by a device on the spindle s, being open when the spindle is back in zero position and closed as soon as it leaves that position. The release circuit is further controlled by the 85 cut-off relay N, through a back contact 11 connected to the wire 12 and coöperating with the armature n², which is grounded through the wire 12. In order that the relay magnet s' may be energized, therefore, it is necessary for the switch to be set away 90 from its normal position, and for the relays M and N both to be deenergized. This condition is only brought about when a connection has been made and the subscribers 95 have hung up their receivers.

The switch S has in its bank trunk contacts s⁴, which coöperate with the switch wipers s⁵, and the test or signaling contacts s⁶ which coöperate with the wipers s⁷. The multiples of these bank contacts which as 100 shown in Fig. 1 are of course supposed to be distributed in different switches, the wires from each trunk being multiplied to as many lines switches as may be desired. A convenient arrangement contemplates 100 multiples, there being ten trunks, and each trunk being represented by a multiple contact in each line switch of 100 lines. Each line thus has access to ten trunks, and each line switch need only have ten sets of contacts s⁴, s⁶ in its banks. Instead of using the 110 rotary switch, I may make the single motion of the switch vertical, the contacts s⁴, s⁶ then being arranged in vertical rows and the wipers s⁵, s⁷ being stepped up along the rows 115 by means of the magnets s². When the release magnet s' works, the spindle s will then be restored by gravity, and the springs a' and b' will be placed beneath the spindle 120 so that its weight will open them.

The contacts s⁴, s⁶ are the terminals of the trunk circuits, and one of these trunk circuits is shown in Figs. 1 and 3, leading to a selector switch S². This trunk is marked 13, 14, 15 and 16, and its extensions in Fig. 3 130

are marked 17, 18. A pair of condensers C is interposed in the circuit, for the purpose of separating the same into two portions for battery currents, these currents being fed both ways in the operation of the system. 5 Across the answering end of the trunk, 13—14, are bridged the two relays R and R', with the main battery B between them. The tip relay R' is grounded, and the sleeve relay R is connected to the live side of battery, which is the usual arrangement in circuits of this type. The tip relay R' responds to the act of the calling subscriber and controls the clearing out of the automatic apparatus; the sleeve relay becomes energized when the switch S picks out an idle trunk, and then closes the circuits of the magnets R² and R⁴, which are respectively the stepping magnet of the secondary 10 or operating selector switch S', and a locking relay serving also as a cut-off relay for shifting the control after the operator's circuit is connected. The functions of those several relays will best appear from the 15 statements of their operation hereafter. The relays R⁵ and R⁶ are combined cut-off and repeating relays. The relay R⁵ when energized over the operator's wire 20 pulls up its armature, breaks apart the wires 15 and 17, and connects the latter to the wire 21 leading to the battery wire 3, so as to send an impulse of current through the trunk wire 17. Similarly, when the relay R⁶ is energized over the operator's wire 19, 20 it pulls up its armature to break apart the wires 16 and 18, and connects the latter to the wire 22 and thence to the battery wire 3, thus sending an impulse of current forward over the trunk wire 18. When both 25 of these relays R⁵ and R⁶ are simultaneously energized, they connect the operator's wires 19 and 20 to the wires 15, 16, respectively, so that the operator may connect her telephone to said wires 15 and 16 and communicate with the calling subscriber. 30 The multiple test contacts s⁶ are normally connected by a wire 23 to the contact 24 and thence through the contact 25 and conductor 25' to the battery wire 3, whereby the contacts s⁶ are connected directly to the battery B, so the test condition of an idle trunk is that these contacts have their potential raised to the full voltage of the main battery. When the relay R' becomes energized, 35 however, which, of course, occurs when the trunk is busy, the contacts 24 and 25 are separated by armature r' and the battery connection made through the resistance 27 whereby resistance 27 is interposed between the battery and the contacts s⁶. This condition continues while the circuits are in use, and suffices to give a busy test, since the cut-off relay N of such line is connected through a wire 28 to the wiper s⁷ of the line switch S. This wiper passes over the contacts s⁶ when the switch is operating and the cut-off relays are so wound and adjusted that they will pull up on direct battery connection but will not pull up on the connection through a resistance 27. Their arrangement is such, however, that any relay which has already been pulled up will hold up on one-half full the current and therefore on the flow through the resistance 27, so that when the wiper s⁷ of a line switch passes over the terminal s⁸ of trunks which are already busy, the relay N of the calling or testing line will not pull up but the relays of the lines already in use will continue to hold up. 40 The trunk wires 17 and 18 extend as shown in Fig. 3 to the side-switch arms s¹⁰ and s¹² of the selector switch S². This switch is of the Strowger type referred to in the beginning of my specification, having a main spindle arranged for both vertical and rotary movements, this spindle being placed at the axis of a set of contacts arranged in ten rows of ten each. Carried on the spindle are talking-circuit wipers s¹⁶, 45 which coöperate with the bank contacts s¹⁸ and a test wiper s²⁰ which coöperates with the multiple test contacts s²². The switch spindle is stepped up to bring its wipers opposite the desired row of contacts by means of the so-called vertical magnet v controlled through a relay V; and the rotary movement of the switch is brought about by means of a vibrator magnet v' which makes and breaks its own circuit as it vibrates and is controlled by the relay T when the side switch arm s⁸ is in its second or intermediate position. 50 It is unnecessary to give here any extended description of the circuits and apparatus of Fig. 3, all of these being old and well known to those skilled in the art. Q is a release relay of the switch and q is the release magnet governed thereby. The other parts of the apparatus as well as the circuit connections will sufficiently appear from the statement of operation herein-after. 55 S³ designates a connector switch which is designed to coöperate with a selector switch S². It has a similar spindle carrying wipers s²⁴ and s²⁵. The test is made on the tip or upper side of the line. This switch also contains line contacts in its banks arranged in rows of ten each. The spindle is stepped up to bring the wipers s²⁴ opposite the desired row by means of a so-called vertical magnet v and is rotated step by step by means of a so-called rotary magnet v², which in this case is not a vibrator but responds to distinctive current impulses, since the desired line is identified with a single pair of contacts only, and therefore the row of contacts must be selected and the pair of contacts in the row afterward picked out. 60

by the wipers, before testing. In this resides the principal difference between the connector and selector switch, the purpose of the selector switch being to pick out and connect with an idle trunk line in any desired group. In the operation of the selector switch, therefore, the spindle is stepped up by means of definite and distinctive impulses to the row of contacts s^{18} and s^{22} representing the desired group (which may be either thousands or hundreds and in this case hundreds), and after that, when the side switch has taken one step the rotary magnet v' takes control of the switch and steps the spindle around continuously as long as the wiper s^{20} finds ground on the contacts s^{22} . When this ground fails (the busy contacts being grounded and the idle one open) it means that an idle contact has been reached, and thereupon the side switch is moved a third step to cut off the rotary magnet and stop the wipers upon this ungrounded or idle contact.

The connector circuit contains a pair of condensers C' for the reason that the forward impulses which work the switch must not be confused by the battery current supplied to the called subscriber. We may assume that the switches of Fig. 3 are both in the same building with the apparatus of Figs. 1 and 2 although this is not at all necessary, and in such case the battery B shown separate in the two figures is of course the same battery. For the purpose of supplying talking current to the called subscriber, I connect this battery to the sleeve conductor 44, of the connector switch, through a relay R^s , and I ground the tip conductor 43 through the relay R^7 which is the same as connecting it back to battery. Thus, the main battery is also bridged across the conductors 43 and 44 through the relays R^7 and R^s which as in the case of the relays R and R' in Fig. 1 are wound to approximately 100 ohms each, but present high impedance to voice currents. R^s is the ringing relay, which controls the application of the ringing generator G to the called line and is itself controlled on the one hand by the relay R^{10} and on the other by the commutator K , which may be common to all the ringing relays of the exchange. The circuit of the ringing relay is indicated at 45, 46, 47, 48, 49 and 50, being terminated at 55 the ground through the commutator on one end and at the battery wire 3 on the other end. This circuit is controlled by the relay R^s , and this relay does not become energized until the side-switch arms s^9 , s^{11} , s^{13} and s^{15} have made their last step so that the conductors 43 and 44 are completed from the condensers C' to the wipers s^{24} and s^{25} . Before this last step of the side-switch is taken, the wipers s^{24} and s^{25} have been placed upon the terminals of the wanted

line, and the release relay Q' has been applied to the tip side of the line for the purpose of testing. The circuit of this relay is as follows: 51, 52, 53, 54, 55, s^{15} , 56 to tip wiper s^{24} . If the line wanted is busy, there is a ground on the tip side, either by way of a relay R' or by way of a relay R^7 , depending on whether the line originated the call upon which it is engaged, or was called by some other party. In either case the test or release relay Q' will receive current; but if there is no ground because the line wanted is idle, then the test relay remains unaffected, the talking circuit is completed, and the sleeve relay R^s becomes energized by current passing to the wiper s^{25} and thence through the multiple contact s^{26} (see Fig. 1) and the cut-off relay N to ground. The cut-off relay there-upon pulls up and the ringing relay circuit is at the same time completed, so that the commutator K takes control thereof. It will be observed that this circuit 46-47, passes through a back contact on the relay R^{10} , which is controlled on one side by a pair of contacts under the foot of the spindle switch s^8 , and on the other side by front contacts of the tip relay R^7 which does not pull up until the called subscriber answers. When this occurs, the relay R^{10} becomes energized, locks itself by way of wires 50 and 51, and opens the ringing relay circuit 46, 47, 48, etc. The relay R^s is controlled by the subscriber in the intervals of ringing, for it will be observed that the commutator K has segments whereby it closes the ringing circuit at intervals only. While this circuit is open, therefore, and the relay R^s deenergized in consequence, the subscriber has control of the relay R^7 . In order that the relay R^s may remain energized through the ringing intervals, I provide a special battery connection, as shown.

The arrangement of switches shown in Fig. 3 is sufficient for exchanges up to 1000 line capacity; but in order to provide for more than 1000 lines, another set of selector switches is required, interposed between the trunk ends of Fig. 1 and the switch S^2 of Fig. 3. The capacity of the exchange can be increased indefinitely without altering those circuits by adding these sets or groups of switches in the well understood manner. The selector switches all have the same circuit as that shown at S^2 and therefore I have considered it unnecessary to multiply illustration by showing more than one. It is within the power and skill of every person having a fair knowledge of the automatic art to add as many sets of selectors as may be desired. Regardless of the number of switches, the method of operation, which has an important bearing upon the operator's equipment, is to send the selecting or working impulses over the trunk wire 17, 130

which is commonly called the vertical wire, and to send the controlling impulses over the trunk wire 18 which is commonly called the rotary wire. These so-called rotary impulses serve to work the side switch magnets 'I' and 'T', and thereby to shift the side switches so as to bring into play successively the vertical and rotary magnets, the test relay, etc.

- 10 Referring now to the lower part of Fig. 1 and to Fig. 2, there is therein shown an operator's equipment and its selector switch for connecting a calling trunk therewith. The selector switch is marked S' and is 15 similar in its construction to the primary selector switch S . It has a spindle s^{28} and wipers s^{29} , s^{30} and s^{31} . It is rotated by means of a pawl and ratchet actuated by a rotary vibrator magnet R^2 , and it is held in 20 any position to which it is turned by a stop pawl controlled by the release magnet s^{33} . The circuit of the rotary vibrator magnet is closed through an interrupter I' , similar to I , by the sleeve relay R of the trunk and 25 opened by the relay R^4 , which is controlled by the relay R^5 , which receives current when an idle operator's set has been connected with the trunk. The release magnet s^{33} has its circuit controlled by the relay R^{11} being 30 connected in parallel with the signal light L between the point x and ground. The relay R^{11} is initially controlled by the relay R^{14} which has its circuit made through the switch wiper s^{31} after that wiper has stopped 35 upon the contact s^{36} which is connected through contacts of relays R^4 and R of the connected trunk to ground. The wipers s^{29} and s^{30} of the operator's selector switch will then rest upon the contacts s^{34} and s^{35} , respectively, which are respectively connected 40 to the operators' wires 19 and 20, the switch being stopped in this position by reason of the energization of the relay R^{11} whereby the circuit of the rotary step by step magnet R^2 is broken. It will now be apparent that 45 when a subscriber's line has been connected with a trunk that the sleeve relay R of that trunk will become energized and a switch S' of an idle operator's set will start up from zero and the wipers s^{29} , s^{30} and s^{31} 50 will sweep over the bank contacts s^{34} , s^{35} and s^{36} , respectively, until these wipers reach the contacts connected with the trunk which has been connected up with the calling 55 subscriber, when the switch S' is stepped. After the operator has performed her functions and the connection through the trunk wires 17 and 18 is completed to the wanted subscriber's line, the release 60 magnet s^{33} restores the switch S' to its zero or inoperative position.

In order to prevent more than one operator's selector switch from being started by a call upon a trunk, interlocking means is 65 employed, which means is shown in Fig. 8,

taken in conjunction with Fig. 1, portions of the apparatus, not necessary to an explanation of the feature under consideration being omitted from Fig. 8.

Referring to Fig. 8, a back contact of the 70 armature on each of the relays R^4 , $1R^4$, $2R^4$, etc., of the trunks, is connected with a common conductor 80. The armatures referred to are connected, respectively, to ground through armatures and front contacts of the 75 relays R , $1R$, $2R$ etc. It will thus appear that while a relay R^4 , $1R^4$, or $2R^4$ of a trunk is deenergized and the relay R , $1R$ or $2R$ of the same trunk is energized, which is the condition when a trunk has been connected 80 to a subscriber's line and before an operator's equipment has been connected thereto, the conductor 80 is connected with ground. One terminal of each of the stepping magnets R^2 , $1R^2$ and $2R^2$, etc. is connected with 85 the conductor 80 and it will therefore be apparent that when any trunk is connected with a calling subscriber's line all of the stepping magnets of the switches S' , $1S'$, $2S'$, etc., corresponding to the operator's equipment will be grounded. The selection of which one of the operators' selector switches is to be operated depends upon the connections of those terminals of the stepping magnets which are not grounded as above described. The ungrounded terminal of each of the stepping magnets is connected through an interrupter I' , $1I'$ or $2I'$, as the case may be, to the back contact of an armature of a relay R^{11} , $1R^{11}$ or $2R^{11}$ of its 90 respective operator's equipment, while each of the armatures referred to is connected to a front contact of its corresponding armature in an adjacent equipment so that when one of these armatures is moved to break 95 the connection of the stepping magnet of its own equipment it forms a connection for the corresponding armature of another equipment. It will be noted, however, that one of these armatures is an exception to the 100 general statement just made for, being at one end of the series of operator's equipments it is connected directly to battery.

Let it be assumed that all of the operator's equipments are idle and that any one of the 115 trunks has been connected with a subscriber's line. The conductor 80 will then be grounded as before indicated and, it will be seen that the circuit of the stepping magnet of the selector switch S' only will have its ungrounded terminal connected with battery through its interrupter, the battery connections of the stepping magnets $1R^2$, $2R^2$, etc., being broken at the front contacts of the armatures of the relays R^{11} , $1R^{11}$, $2R^{11}$, etc., 120 respectively. The battery connection of the stepping magnet R^2 being thus made through the armature of the relay R^{11} and its back contact, this magnet will be intermittently energized and the switch S' will 125 130

be stepped into position to connect the trunk with its operator's equipment. When this connection has been formed, the relay R^4 , $1R^4$, or $2R^4$ according to which trunk is connected, will be energized and, attracting its armatures will break the ground connection to the wire 80 whereupon the circuit of the magnet R^2 will be broken and the switch S' will stop. The connection of the operator's equipment with the trunk also results in the energizing of the relay R^{11} which thereupon attracts its armatures and breaks the battery connection of the stepping magnet R^2 between the armature of that relay and its back contact as before referred to. Any subsequent forming of a ground connection for the wire 80 by a calling trunk will not, therefore, form a circuit for the stepping magnet R^2 while the operator's equipment to which it corresponds is in use and therefore the relay R^{11} energized.

The operator's set corresponding to the switch S' being in use and the armatures of the relay R^{11} being attracted, thereby disabling the stepping magnet R^2 , it is to be noted that the armature at which the circuit of the stepping magnet just referred to is broken, has now come against its front contacts and thereby establishes a battery connection from one terminal of the stepping magnet $1R^2$ of the selector switch $1S'$ through the interrupter $1I'$, conductor 81 and armature of its relay $1R^{11}$ and its back contact and thence through conductors 82 and 83 through an armature and front contact of the relay R^{11} to battery. Any grounding, therefore, of the conductor 80, which is occasioned by the connection with a subscriber's line of a trunk, results in the intermittent energizing of the stepping magnet $1R^{11}$ and the stepping of the selector switch $1S'$ into position to connect the trunk with the operator's equipment corresponding to the switch. In a similar manner to that described in connection with the operator's equipment corresponding to the switch S' , the connecting of the equipment corresponding to the switch $1S'$ will result in the opening of the battery connection of the stepping magnet of the last mentioned switch and the closing of such connection for the stepping magnet $2R^2$ of the next operator's equipment which will be set into operation by the next calling trunk. In a similar manner the connection of the operator's equipment corresponding to the switch $2S'$ will result in the forming of a battery connection for the stepping magnet of the succeeding equipment and so on to the limit of the apparatus.

From the foregoing it will be apparent that, as the battery connection of only one operator's stepping magnet is made at a time, it will be impossible for more than one of the operator's selector switches to be

started at a time or by a single call. It will further be observed that where the simultaneous use of several operator's equipments is required, the equipments so used will be successively selected from one side of the apparatus to its limit at the other. With the apparatus thus far described for securing the successive connection of operator's equipments, if the stepping magnet of one equipment has its connection made through another previously selected equipment and the equipment last mentioned were to have performed its function and have been cleared out, the circuit of the stepping magnet of the former would be broken, and, the selector switch controlled by that magnet being in process of being stepped into connecting position, the switch would be stopped in whatever position it might happen to be at the time of the breaking of the circuit of its stepping magnet and confusion might result. To avoid such a contingency, means is provided for preventing the breaking of the battery connection of the stepping magnet of a switch after such connection has once been made, until the connecting operation has been completed, regardless of whether equipments through which the circuit of the particular magnet is made are cleared or not. The specific means shown for accomplishing this end consists in the provision at each operator selector switch, except that one in which the circuit of the stepping magnet is made directly to battery of contacts a^2 and b^2 . In other words these contacts are provided at every selector switch which has its battery connection made through another equipment. Each pair of the contacts referred to is adapted to be opened when its switch is in its initial position but to be closed in all other positions of the switch. The mechanical construction of a switch having these contacts is shown in Figs. 5 and 6. One of each pair of contacts is connected with battery while the other is connected with the conductors as 82 and 83 leading to another equipment and through which the battery connection of the stepping magnet as $1R^2$ is made. It will now be apparent from an examination of Fig. 8 that, the contacts as a^2 and b^2 of any switch being open at the initial position of the switch, that the initial battery connection of its stepping magnet as $1R^2$ (except of course that equipment which has direct battery connection) is made through another equipment or equipments but that after such connection has been made and a selector switch has been started, circuit of the stepping magnet of that switch will be maintained until the stepping operation is completed, regardless of whether the equipment or equipments, through which the initial connection was made, is or are cleared out or not.

In the lower part of Fig. 2, I have shown the apparatus which appears in front of one operator, consisting of a set of buttons only. Above these in the figure I have shown a set of wheels or sections of a drum with the co-operating springs, the motor and the common commutator of the central office sending machine. This machine furnishes the impulses by which the selector and connector switches are worked in order to select the line wanted, and the number of impulses sent as well as their arrangement is determined by means of the operator's keys or buttons. These keys are in three sets, K, K' and K'', each set having ten buttons controlling contact springs k', k''. The springs k' of all the buttons in each set are joined to a common wire, and the ends of these three common wires are connected together at the point k'', from which point the conductor 70 leads as shown in Figs. 2 and 1 to the multiple contact ⁸⁸⁵ in the bank of the switch S'. The spring k'' of each key is connected to a pen of the appropriate disk or zone on the sending machine drum. When any particular button is depressed therefore it connects its individual wire to the common wire 70. The individual wires of the keys K'' are marked respectively 71, 72, 73, 74, 75, 76, 77, 78, 79, 80. Similarly the individual wires from the keys K' are marked 81, 82, 83, 84, 85, 86, 87, 88, 89, 90, and the individual wires of the keys K are marked 91, 92, 93, 94, 95, 96, 97, 98, 99, 100. In practice these keys are arranged with the strips perpendicular to the front of the desk, the units strip on the right hand side, the tens strip next in order to the left, and so on. In the present drawings however for convenience, the keys are arranged in horizontal rows, with the units row at the top. The sending machine comprises the main commutator D, having a brush d connected to the main battery, and riding over its segments so as to produce regularly recurring makes and breaks in a continuous series. In practice this commutator is made with a pair of spring contacts and teeth or cams are formed on the body of the commutator to work these springs up and down, but for convenience of illustration I have shown the brush resting directly on the periphery of the disk. With such a construction in actual practice and considering that this commutator will carry a large number of switching impulses simultaneously, I prefer to make the brush d of carbon. This is a detail, however, which may be varied at will and does not affect the invention.

The commutator D is graphically shown as carried on a shaft d' which extends through all of the number wheels forming both the mechanical and electrical connection therewith. The mechanical connection is not shown in the drawing but the electrical

connection is indicated by a wire marked d''. The number wheels are shown at d', d'', d'', d'', d'', d'', d'', d'', d'', d'', each having a tooth or raised segment of a suitable length to cover the space of the number of teeth on the commutator D equal to the number of impulses the particular wheel is to transmit. Thus the first wheel d' has a single tooth d'¹¹, approximately equal in length to only one tooth on the main commutator. The second wheel has a single tooth d'¹² approximately equal in length to two teeth on the commutator and so on. In other words, instead of using a set of number wheels each of which makes and breaks through a number of teeth, I have shown all the makes and breaks on the main commutator, and in order to send any desired number of impulses, I select a wheel which will maintain connection with the commutator while the desired number of impulses are being produced and are then cut off therefrom. Another peculiarity of the arrangement is that the makes and breaks on the number wheels d', d'', d''', etc., are made during the passage of gaps on the main commutator when there is zero potential, and hence there will be no sparking at the number wheel contacts. In order to do this I may either subdivide the commutator surface evenly and equally into alternate conducting and insulating segments and then make each number wheel tooth slightly longer than that of the particular tooth to which it corresponds, or I may make the conducting portions on the commutator smaller than the insulating portions and make the number wheels teeth of lengths equal to the exact multiple of a unit subdivision.

It will be observed that there are four sets of pens on the number wheels. These will accommodate four sets of keys K', K'', etc. If a greater number of digits appear in the numbers to be transmitted, the wheels must be provided with additional sets of springs. The set K has its individual wires connected to the first set of springs d'¹³, the set K' has its individual wires connected to the set of springs d'¹⁴, and the keys K'' are similarly connected to the spring pens d'¹⁵. The general direction of rotation of the commutator and the various wheels connected to it is clockwise as shown by the arrows in Fig. 2, and the teeth on the wheels come into contact with the spring pens in the order d'¹³, d'¹⁴, d'¹⁵. Thus the number set up on the set of buttons K is transmitted over the wire 70 first, then follows the number set up on the buttons K' and so on. Thus for the number 468 the operator would depress the fourth button in the set K. The sixth button in the set K' and the eighth button in the set K''. By tracing the circuits it will be found that when the controlling circuits are

closed, which occurs at the beginning of a rotation when the wheels are all in the position shown in Fig. 2, current will pass from the main battery to the commutator D, 5 thence to the wheel d^4 , thence by wire 94 to the fourth key in the set K and thence to the wire 70 and so on to the wire 20 and the relay R^s in Fig. 1 which repeats the impulses over trunk wire 17 to the switches. 10 As the wheels continue their rotation this circuit will be broken after four impulses have been transmitted, and then a new circuit will be formed carrying current from the battery through the commutator to the 15 sixth wheel d^6 , and thence from the second spring d^{14} on that wheel through the wire 86 to the key which is closed, thence the wire 70 and thence again to the relay R^s which repeats to the switches. After these 20 impulses have been sent by this route, this circuit will be broken and a new circuit will be formed from the main battery through the commutator D to the eighth key wheel to the third pen thereon, d^{15} , thence to the 25 eighth key in the set K^2 , which has been closed, thence to wire 70 and to the relay R^s as before. The closures between the wheels and successive sets of springs are arranged to be separated by intervals, during which 30 no current at all flows to the wire 70. These intervals are necessary in order to permit the switching circuits to be arranged so as to reduce the proper results in response to the successive sets of working impulses. In 35 other words, having shown therein a set of Strowger switches, I must provide not only the vertical or working impulses in groups, but I must also provide the interposed or rotary impulses between said groups. This 40 is accomplished by means of the wheel d^{17} , which has four teeth in quadrature, and all adapted to make contact with the single pen d^{18} , which is connected by the wire 170 to the multiple contacts s^{34} in the banks of 45 the various selector switches S' , and thence through the wire 19 to the relay R^s , which repeats the rotary impulses over the trunk wire 18 to the switches. The wheel d^{17} is insulated from the shaft d^o , and is ground- 50 ed through the wire 101, this being necessary because the relay R^s is connected on the other side to the battery wire 3. In other words, the repeating relay R^s , which is controlled by the number wheels, is the 55 grounded relay and so the number wheels take battery impulses from the commutator; but the relay R^s is on battery, hence the rotary wheel d^{17} uses the ground to work the relay. The reason I make one of these 60 relays grounded and the other connected to battery is in order to pull them both up simultaneously when the operator has her telephone set bridged across the wire 70 and 170 in Fig. 2.

65 Hitherto the selector switches referred to

as S and S' have been referred to only as regards the electric circuits and contacts with which they are associated and in this connection the diagrammatic illustrations in Fig. 1 have been sufficient. Mechanical features of a switch adapted to perform the functions of the switch S S' of Fig. 1 are shown in Figs. 5 and 6. This switch comprises a frame a on which is mounted a bank b of contacts consisting of ten rows of 70 contacts of three contacts each. The contacts of different rows are adapted to be successively engaged by wipers c, d, e , which are fixed upon the rotatable shaft f , the contacts c, d, e , being respectively insulated from each other. A spring g interposed between the shaft f and a stationary part as the frame, tends to rotate the shaft f to one limit of its movement, when the contact arm carried by the shaft will not rest upon any 75 of the bank contacts as shown in Fig. 5. Fixed upon the shaft f is a ratchet h . Adapted to engage with the ratchet h are a holding pawl i and stepping pawl k . The pawl i is pivoted upon the frame and its nose is normally held in engagement with the ratchet by means of a spring l . The pawl k is pivoted to the armature m^2 of the stepping magnet R^2 , which armature is in turn pivoted to the frame of the magnet or 80 upon any other suitable portion. The armature m^2 is normally held retracted by a spring o while the nose of the pawl k is thrown outwardly by means of a spring p , extending between the armature m^2 and the 85 tail of the pawl k . The outward movement of the nose of the pawl k is limited and it is guided in its movement by a stationary pin q^2 .

In order that the holding pawl i may be 90 disengaged from the ratchet h so that the contacts upon the shaft f may be returned to their normal position under the influence of the spring g , a magnet s^{33} known as the release magnet is provided. The armature s^3 95 of the release magnet is retracted by means of a spring t , this armature being limited in its outward movement by a nut u in a screw-threaded engagement with the screw y^3 mounted upon the frame of a magnet and 100 extending through the armature s^3 . Obviously the nut u is capable of adjustment along the screw y^3 to permit greater or less movement of the armature s^3 . Carried by the armature s^3 of the release magnet is a 105 resilient arm w which carries a ratchet tooth x' adapted to engage with the lower end of the holding pawl i . An arm y mounted upon the armature n^2 of the stepping magnet overlaps one end of the arm w 110 and is adapted to draw down one end of that arm so that the lower end of the pawl i will clear the tooth x' when the armature of the stepping magnet is attracted.

The operation of the apparatus is as fol- 115

lows: Assuming the parts to be in position as shown, as impulses are supplied to the stepping magnet its armature will be attracted a number of times equal to the number of the impulses and at each attraction the pawl k will be thrown forward into engagement with the ratchet wheel and will move that wheel forward a distance depending upon the adjustment of the various parts, which are so adjusted that at the first impulse the wipers upon the shaft f will be moved into engagement with the first row of bank contacts and will be moved to a succeeding row upon each impulse thereafter. The shaft and wipers which it carries will be prevented from retrograde movement by the holding pawl which is forced into engagement with the ratchet h by its spring. A desired row of the bank contacts having been reached in the manner described and the object for which the connection was established having been accomplished, it becomes necessary to return the wipers to their zero or normal position in readiness for another operation as just described. This restoration is effected by deenergizing the release magnet s^3 , it having been previously energized, when its armature will be retracted, drawing the tail of the holding pawl i with it, and the nose of that pawl will be disengaged from the ratchet h and the wiping contacts will be returned to their initial position. In the next selective operation of the switch, however, it is necessary that the holding pawl i shall engage with the ratchet h to hold the contacts in any position to which they may be stepped. It, therefore, becomes necessary to release the pawl i from the arm prior to the succeeding stepping operation. This is accomplished by means of the arm y which upon the first energization of the stepping magnet and the attraction of its armature, will draw down with it the free end of the resilient arm w thereby freeing the pawl i whereupon its nose will be thrown against the ratchet h by the spring l . The contacts a^2 and b^2 operated by the projection z are useful in some applications but are not used in the apparatus herein illustrated and so will not be further referred to.

It will be noted in regard to the switch just described that the release of the wipers occurs upon the deenergization of the release magnet, the holding pawl being in position to engage the ratchet and restrain the wipers so long as the release magnet remains energized after having once been excited. It may be, however, as in the case of switch S , that it will be of service for the release of the wiper contacts to occur upon energization of the release magnet and for the holding pawl to be disengaged from the ratchet even though the release magnet may be deenergized. A structure adapted for opera-

tion in this manner but in other respects like the switch just described is shown in Fig. 7. On reference to this figure it will be seen that the holding pawl i' is pivoted at e' and its nose is normally held in engagement with the ratchet by the spring d' . The tail of this holding pawl is adapted to be engaged by armature s^3 of the release magnet s' . When the release magnet is energized, its armature is attracted and the holding pawl i' is moved against the spring d' so that it clears the ratchet, when the wiper contacts are free to return to their initial position. When the armature s^3 is attracted, it carries with it the resilient arm w' , the tooth x^2 of which latches behind the stationary detent z^4 . The holding pawl is thus locked away from the ratchet until, at the first impulse in the stepping magnet s^2 at the beginning of another selective operation the arm y' is drawn downwardly and unlocks the arm w' from the stationary detent, whereupon the holding pawl comes into engagement with the ratchet. The operation of this switch is in all respects similar to that of the switch in Figs. 5 and 6 except as to the releasing means above indicated.

The operation of the system can be best set forth by tracing the connections and noting the operations of the various parts of the apparatus which are involved from the time a call is initiated at a subscriber's station until the conversation has terminated and the apparatus has been restored to its normal condition. Let it be assumed that a subscriber at a station as A desires to converse. He removes the receiver from its hook when the latter rises and establishes a connection, through his transmitter and receiver, between the lines 1 and 2. A circuit is then established from the free terminal of the battery B through the wire 3, line relay M , armature n , line 1, subscriber's set, line 2 and armature n' to ground. The relay M , being thus energized, attracts its armature m a circuit then being established from the free side of battery B through conductors 3 and 6, armature m , interrupter I, conductor 8 and stepping magnet s^2 to ground. The magnet s^2 is then intermittently energized, as its circuit is made and broken by the interrupter, which results in the reciprocation of the stepping pawl k (see Fig. 7) and the stepping forward of the wipers of the switch S from one row of bank contacts to the next at each energization. In the initial position of the switch, the circuit of the magnet s' is broken at the contacts a' , b' and the switch does not move from this position until the relay M is energized and then although the contacts a' and b' are closed, the armature m is attracted and the connection between that armature and wire 10 is broken. The release magnet being thus deenergized, the

holding pawl s' is in engagement with the ratchet wheel and holds the wipers in any position to which they may be stepped.

The wipers are stepped from one row of 5 bank contacts to the next in the manner described until the wipers s^6 and s^7 rest upon the contacts s^4 and s^6 of an idle trunk, when the circuit of the cut-off relay N is made from the ground through the relay, 10 wire 28, wiper s^7 , contact s^6 , wire 23 and contacts 24 and 25, to conductor 3, connected to the free side of the battery B, there being negligible resistance in the circuit of the relay N.

15 When a connecting trunk is in operation or "busy," the relays R and R' are energized when the circuit from the contact 24 through the branch connection of negligible resistance will be opened. A connection, however, may be traced from the contact 24 20 through the resistance 27 to the conductor 3. As has been before pointed out, this resistance is of such magnitude that it will permit sufficient current to flow, so that the 25 relay N will hold its armatures after they have been once attracted, but the current will be insufficient to cause the relay N to initially attract its armature. It will now appear as the wipers s^6 and s^7 pass over 30 the contacts of "busy" connected trunks, that the armatures of the relay N will not be attracted and the stepping of the switch S will continue until the test wiper s^1 comes against the test contact s^6 of an idle connecting trunk when the circuit of low resistance will be formed through the relay N of the calling subscriber whereupon the armatures of the relay N will be attracted. The armatures n and n' of the relay N being 35 thus removed from their back contacts, the circuit of the line relay M will be broken and its armature m will fall back and come into contact with the back contact 9, while the circuit through the wire 8 of the stepping 40 magnet s^2 will be broken by the armature m and the stepping of the switch will cease.

The contacting of the armature m and the back contact 9 forms a connection whereby 45 the circuit of the release magnet s' is completed from the wire 3 through conductor 6, armature m , conductor 10, magnet s' and contacts a' , b' (the switch S being out of its initial or zero position) to conductor 12. 50 Inasmuch, however, as the armature n^2 is attracted by the relay N, the circuit of the release magnet is broken between the armature referred to and its contact 11. The holding pawl of the switch, therefore, is in 55 engagement with the ratchet upon the switch shaft so that the wipers are maintained in the position to which they have been stepped.

The switch S having been stepped into position, as described, circuit may be traced 60 from the free side of the battery B through

the relay R to sleeve side 14 of the trunk thence through one of the multiple contacts s^1 , one of the wipers s^5 , the extension 5 of the subscriber's line, armature n' of the relay N, conductor 2 of the subscriber's line, 70 the subscriber's instrument, conductor 1 of the subscriber's line, armature n of the relay N, extension 4 of subscriber's line, the other wiper s^5 of the switch S, the other multiple contact s^4 , the tip side 13 of the 75 trunk and the relay R' to ground. A circuit having thus been completed, the armatures of the relays R and R' are attracted. The attraction of the armatures $2r$ and $3r$ operate to close the circuit of the stepping 80 relay R^2 and the test contact s^{36} of the operator's selector switch with ground. The circuit of the relay R^2 may be traced from the free side of the battery B through the conductor 3, conductor 68, interrupter I', relay R^2 , conductor 80, armature $1r^4$ of the relay R^4 , conductor 85, armature $3r$ and conductor 86 to ground. From the test contact of the switch S', circuit may be traced through the conductor 101, armature r^4 , conductor 102 and armature $2r$ to ground. The armatures $2r'$ and $3r'$ are connected by a conductor 105 with the conductor 106, which, when the relay R^4 is energized and its armature $2r^4$ is attracted, is connected through 90 that armature and a conductor 107 and conductor 3 with the free side of the battery. When the armatures $2r'$ and $3r'$ are not attracted, the relay R' being deenergized, 95 these armatures will be respectively in connection with the conductors 108 and 109 which are, respectively, connected to the tip and sleeve sides 15 and 16 of the trunk, connected so that when the relay R' is deenergized both sides 15 and 16 of the trunk 100 will be connected with battery.

The magnet R^2 being intermittently energized will reciprocate its pawl, (see Figs. 5 and 6 and descriptions thereof) stepping the switch forward. When the wiper s^{31} rests 110 upon the contact s^{36} , circuit may be traced from the ground through armature $2r$, conductor 102, armature r^4 , conductor 101, contact s^{36} , wiper s^{31} , conductor 49', armature $1r^{11}$, conductor 50' and magnet R^{14} to battery. In coming against its front contacts the armature $2r^{11}$ establishes connection for the stepping magnet of the next operator's selector switch as hereinbefore described. The attraction of the armature r^{14} against 120 its front contact closes the circuit from the ground through relay R^5 , conductor 52', conductor 20, contact s^{35} , wiper s^{30} , conductor 53', armature r^{14} , conductor 54', make-before-break contacts 55' and 56', relay R^{11} , 125 conductor 57', and armature r^{13} to battery. The relays R^5 and R^{11} are thus energized and their armatures attracted. As the armature r^{11} comes against its front contact 56', the contacts 55' and 56' are separated 130

thus breaking the circuit just traced, the ground connection of the relay R^{11} being however maintained through the armature r^{11} and contact 56'. It will be seen that the relay R^5 has been momentarily energized and that its armature r^5 has been momentarily brought against its front contact thereby momentarily closing the circuit of the relay R^4 from the ground through armature 3r., conductor 85, relay R^4 , conductor 106, conductor 59' and armature r^6 to battery. The relay R^4 is then energized and attracts its armatures, the armature 2r⁴ coming against its front contact and locking battery connection on the relay R^4 so that its circuit is maintained after the relay R^5 has been deenergized. The attraction of the armatures r^4 and 1r⁴ breaks the connections of the trunk with the operator's stepping magnet and its connections with the multiple contacts s^{36} of the operators' selector switches, the ground connection for the relay R^{14} , formerly made through the contact s^{36} , being maintained by the armature 1r¹¹ which has been attracted against its front contact and which is connected to ground. The armature 2r¹¹ has also been attracted against its front contact whereby circuit is established from battery through conductor 68, armature 2r¹¹ and the front contact thereof to point α whence a portion of the current passes by light L to ground and the other portion passes through release magnet s^{33} to ground. The release mechanism is thus set to engage the holding pawl of the switch S' (see Fig. 5) and the operator is notified of a call by the lighting of this lamp. Connection may now be traced from battery through relay R^6 , conductor 19, contact s^{34} and wiper s^{39} to conductor 17°. Connection may also be traced from ground through relay R^5 , conductor 52', conductor 20, contact s^{35} , wiper s^{30} , conductor 53' and armature r^{14} to conductor 70.

Referring now to Fig. 2, it will be seen that the conductors 17° and 7° are adapted to be connected by means of the pressure of a button O with the conductors 127 and 128, which lead to an operator's set of usual construction and hence not shown. It will be seen that upon the depression of the button O, that a circuit will be completed from the battery wire at one side of the relay R^6 through that relay the operator's set, and the relay R^5 to ground. Talking current will thus be supplied to the operator's set and also the relays R^5 and R^6 will become energized, whereupon they will attract their respective armatures 1r⁵ and r^6 and one of the operator's conductors 20 will be connected with the trunk conductor 16 while the other operator's conductor 19 will be connected with the other trunk conductor 15. It will now be apparent that the operator's

set and the calling subscriber's instrument will be so connected that conversation may be had.

The operator's set and subscriber's instrument having been placed in conversational communication as described, the operator inquires of the subscriber the number of the wanted subscriber's station. Let it be assumed that this number is 468. The operator depresses the fourth key of the set K, the sixth key of the set K' and the eighth key of the set K². In this manner the conductors 94, 86, and 78 are connected with the common point k^x , these conductors being respectively connected with the pen d^{13} of the drum section d^4 , the pen d^{14} of the section d^6 and the pen d^{15} of the drum section d^8 . The commutator D is driven by a motor M^3 and, the motor supposed in the particular apparatus shown to be normally at rest, it becomes necessary to start the motor and commutator. To accomplish this, the operator depresses the button O' and thereby connects the conductor 130, which is connected to one terminal of battery to the conductor 131 and thence through the conductor 132 to the relay R^{12} and to ground. The relay R^{12} being thus energized its armatures r^{12} and 1r¹² are attracted when circuit will be closed from the battery wire 109 through the last mentioned armature, conductor 133 and relay R^{13} to ground. The relay R^{13} being thus energized will attract its armatures r^{13} and 1r¹³. The circuit of the relay R^{11} to battery through the armature r^{13} is thus broken but this connection is made through the armature r^{12} of the relay R^{12} whereby the control of the relay R^{11} is transferred from the relay R^{13} to the relay R^{12} . Circuit may be traced also from the motor conductor 134 through the armature 1r¹³ and a suitable generator and a motor starter as indicated which may be of any well known type to the other motor conductor 135. The motor will thereupon start up and place the commutator in operation. There is also set in operation a starting disk which is of conducting material with the exception of an insulating segment 136 upon which the pen 137 normally rests. After the motor and with it the commutator, starting disk, rotary disk and drum sections are set in operation by the depression of the key O', as described the pen 137 will ride off the insulating segment and maintain the circuit initially closed, by the depression of the button O'. This circuit being closed the motor, commutator and disks will continue to revolve until the pen 137 again rests upon the insulating segment 136, when the circuit will be broken and the apparatus will stop. During this rotation, first the pen d^{13} corresponding to disk d^4 will be engaged by the contact segment upon the said disk, which is of such a length as to maintain the

contact with the pen during four impulses of current through the commutator. The circuit over which these impulses are sent, may be traced from one terminal of the battery to the brush d thence through the commutator, the conductor d_{10} to the shaft of the drum thence through the drum to the segment of the disk d^4 , the pen d^{18} , the conductor 94, the contacts of the fourth button of the row K to the point k^x thence through the conductor 70 to the contact s^{25} of the switch S', conductor 20 and relay R^5 to ground. At each of the four impulses, the relay R^5 will be energized and attract its armature $2r^5$ against its back contact connected with the battery B. At each impulse, therefore, the tip side 17 of the trunk will be connected with battery and the impulses will be repeated over this side of the trunk to operate the automatic selector and connector switches as before described; the next operation consists of the sending of a rotary impulse, occasioned by the coming in contact with the pen d^{18} of one of the conducting projections upon the disk d^{17} . This action causes the closure of a circuit from the ground through a conductor 101, disk d^{17} , pen d^{18} , conductor 170, contact s^{84} , of the switch S', conductor 19, and the relay R^6 to the battery wire 3. Each projection on the disk d^{17} is of such length as to transmit but one impulse and this impulse passing through the relay R^6 through the circuit just traced, the relay last mentioned attracts its armature $1r^6$ against its back contact thereby connecting the sleeve side 18 of the trunk momentarily with the battery wire 3, when a rotary impulse is transmitted over the sleeve side for working the side switches of the automatic selector and connector switches as before indicated; after the sending of the rotary impulse as described, the conducting segment of the disk d^6 comes in contact with its pen d^{14} when six impulses are sent over the conductor 86 to the point k^x , whence circuit is the same as before through the relay R^5 and six vertical impulses are transmitted over the tip side 17 of the trunk. The disk d^{17} then sends another rotary impulse over the sleeve side of the trunk as before and eight vertical impulses are then transmitted over the tip side by reason of the contact upon the disk d^6 coming in contact with its pen d^{15} , connected with the conductor 78 through which connection is established to the point k^x , the circuit being otherwise the same as before through the relay R^5 , this is followed by the sending of a rotary impulse by the disk d^{17} and then the apparatus is brought to a stop by reason of the pen 137 riding upon the insulating segment 136.

At the close of the operation just described, the wanted subscriber's line, unless it is busy, will have been connected as be-

fore described. The entry of the pen 137 upon the insulating segment 136 at the end of the connecting operation breaks the circuit as before traced through the relay R^{12} which thereupon releases its armature thereby breaking the circuit of the relay R^{11} which in turn releases its armature $2r^{11}$ thereby breaking the circuit of the release magnet s^{33} when (see Fig. 5) the holding pawl i will have its nose removed from engagement with the ratchet upon the switch shaft and the switch will return to its zero position, thus leaving the operator's set idle in readiness to perform the connecting operation for another connecting trunk and its subscriber's instrument. The circuit of the relay R^{13} will be broken at the armature $1r^{12}$ whereupon the motor circuit will be broken at the armature $1r^{13}$.

Connections between the two subscribers having been established as described, the hanging up of the calling subscriber's receiver breaks the circuit at the hook through his instrument thereby breaking the circuit of the relays R and R' whereupon their armatures are released and the circuit of the cut out relay N is broken. The armatures of this relay being released, the line wires 1 and 2 of the calling subscriber are disconnected from their extensions 4 and 5. The armature n^2 being released, connects one of the contacts a' , b' with ground through the conductor 12 and the switch S being out of its initial position, the contacts a' and b' are in contact. The circuit of the release magnet can then be traced from the battery wire 3 through the conductor 6, armature m , conductor 10, magnet s' , contacts a' , b' , conductor 12 and armature n^2 to ground. The release magnet will thus be energized and the holding pawl will be removed from engagement with the ratchet upon the switch shaft whereupon the switch will return to its initial position (see Fig. 7). The magnet R being deenergized, its armature $3r$ will break the circuit of the magnet R^4 . The armature $2r^4$, however, is arranged to act sluggishly when released so that the connection of the conductor 105 with the battery wire 3 is maintained after the armatures $2r'$ and $3r'$ have come against their back contacts. This being the case, it will be seen that the two sides 15 and 16 of the trunk are simultaneously connected with battery, this results in the simultaneous energization of the relays V^2 and V^3 , the circuit of the relay V^2 being traceable from the trunk conductor 41 through the relay V^2 and conductor 65 to ground while the circuit of the relay V^3 is traceable from the trunk conductor 42 through relay V^3 to ground. Relays V^2 and V^3 having thus been energized and their armatures attracted, circuit may be traced from battery wire 52, release relay Q', conductor 53, con⁴ 130

ductor 64, bank contact s^{22} , wiper s^{20} , release relay Q, conductor 38, side switch arm s^{14} and conductor 39 to ground. The release relays Q and Q' being thus energized will attract their armatures when the circuit of the release magnets g and g' of the switches S^2 and S^3 , respectively, will be closed whereupon those switches will be released and will return to their normal positions.

10 I do not claim broadly herein the combination of primary selector switches associated with the lines and secondary selector switches associated with operators' sets, 15 each of the primaries and each of the secondaries containing fixed terminals of connective trunks. Such a combination broadly is disclosed in my prior application Serial No. 327,096, filed July 20, 1906. 20 Neither do I claim herein broadly a semi-automatic system in which incoming calls are distributed among idle connective links, and through secondary mechanism are distributed among the idle operators' positions, 25 the operators controlling selective switches for completing connection between subscribers. Such subject matter is disclosed and claimed in my prior copending applications Serial No. 323,096, filed June 23, 1906; 30 Serial No. 327,096, filed July 20, 1906; Serial No. 369,201, filed April 20, 1907; Serial No. 383,874, filed July 15, 1907; and 35 383,875, filed July 15, 1907. Such subject matter is also disclosed in Letters Patent granted to me July 14, 1914, No. 1,103,898.

The claims in this case are directed particularly to that type of system in which all of the primary and secondary switches have a normal or zero resting position from 40 which they are started into operation and to which they are restored at the end of respective operations.

Having thus described my invention, what I claim and desire to secure by Letters Patent is:

1. In a telephone exchange system, a number of subscribers' lines, a primary selector switch for each subscriber's line, a number of trunks less than the number of subscribers' lines, each of said trunks having at 50 one end multiple contacts in said switches, a first selector switch at the other end of each trunk, an operator's circuit and apparatus including a telephone set and a sending device, and an automatic switch associated with the operator's circuit and containing terminals of a number of said trunks, all of the switches specified being normally in a zero or inoperative position and adapted to 55 be started up to test and connect with bank terminals in their numerical order, substantially as described.

2. In a telephone exchange system, a number of subscribers' lines, a primary selector switch for each subscriber's line, a number

of trunks less than the number of subscribers' lines, each of said trunks having at one end multiple contacts in said primary selector switches, a first selector switch at the other end of each of said trunks, an operator's circuit and apparatus including a telephone set and a sending device, an automatic switch associated with the operator's circuit and containing terminals of a number of said trunks, and restoring means for 75 said switches, substantially as described.

3. In a telephone exchange system, a number of subscribers' lines, a primary selector switch for each subscriber's line, a number of trunks less than the number of subscribers' lines, each of said trunks having at one end multiple contacts in said primary selector switches, a first selector switch at the other end of each trunk, an operator's circuit and apparatus including a telephone 80 set and a sending device, an automatic switch associated with the operator's circuit and containing terminals of a number of said trunks, driving means for the primary selector switches started by the calling subscribers, and driving means for the operators' switches controlled by the primary selector trunks, substantially as described.

4. In a telephone exchange system, a number of subscribers' lines, a primary selector switch for each subscriber's line, a number of trunks less than the number of subscribers' lines, each of said trunks having at one end multiple contacts in said primary selector switches, a first selector switch at 95 the other end of each trunk, an operator's circuit and apparatus including a telephone set and a sending device, an automatic switch associated with the operator's circuit and containing terminals of a number of said trunks, driving means and release or restoring means for said primary selector switches, said driving and release or restoring means being controlled by the calling subscribers and driving means for the operators' 100 switches controlled in the use of the primary selector trunks, substantially as described.

5. In a telephone exchange system, a number of subscribers' lines, a primary selector switch for each subscriber's line, a number of trunks less than the number of subscribers' lines, each of said trunks having at one end multiple contacts in said primary selector switches, a first selector switch at 115 the other end of each of said trunks, an operator's circuit and apparatus including a telephone set and a sending device, an automatic switch associated with the operator's circuit and containing terminals of a number of said trunks, driving means and release or restoring means for the said primary selector switches, said driving means and said release or restoring means being controlled by the calling subscribers, driving 120 means and release or restoring means for 125

130

- the operators' or secondary switches, said driving means and release or restoring means for the operators' switches being controlled in the use of the primary selector 5 trunks, substantially as described.
6. In a telephone exchange system, a number of subscribers' lines, a primary selector switch for each subscriber's line, a number of trunks less than the number of subscribers' lines, each of said trunks having at one end multiple contacts in said primary selector switches, a first selector switch at the other end of each of said trunks, an operator's circuit and apparatus including a 10 telephone set and a sending device, an automatic switch associated with the operator's circuit and containing terminals of a number of said trunks, driving means and release or restoring means for the said primary selector switches, said driving means and said restoring or release means being controlled by the calling subscribers, driving means and release or restoring means for the said operator's switch, said driving means and said release or restoring means for the operator's switch being controlled in the use of the trunks and driving means for the forward or calling selector switches controlled by the operator, substantially as described.
- 15 7. In a telephone exchange system, a number of subscribers' lines, a primary selector switch for each subscriber's line, a number of trunks less than the number of subscribers' lines, each of said trunks having at one end multiple contacts in said primary selector switches, a first selector switch at the other end of each of said trunks, an operator's circuit and apparatus including a telephone set and a sending device, an automatic switch associated with the operator's circuit and containing terminals of a number of said trunks, driving means and release or restoring means for the said primary selector switches, said driving means and said release or restoring means being controlled by the calling subscribers, driving means and release or restoring means for the said operator's switch, said driving means and said release or restoring means for the operator's switch being controlled in the use of the trunks, driving means for the forward or calling selector switches controlled by the operator, and release or restoring means for the said calling selector switches controlled over the 20 lines connected, substantially as described.
- 15 8. In a telephone exchange system, a plurality of subscribers' lines, a primary selector switch for each line, connecting links less

in number than the number of lines having multiplied contacts in said primary selector switches, an automatic impulse sending device, an operators' manual means for controlling said impulse sending device, an automatic switch associated with said operator's controlling means for connecting said sending device with one of said link circuits, automatic switches arranged to be actuated over said link circuits and means for restoring all of said switches to their normal positions.

9. In a telephone exchange system, subscribers' lines, a primary selector switch for each of said lines, link circuits less in number than the number of lines, operators' sending devices, a selector switch associated with each sending device and arranged to select one of said links, automatic means for effecting a talking connection through the impulses from said sending machine and means for restoring all of said switches to their normal inactive positions.

10. In a telephone exchange system, a plurality of subscribers' lines, primary selector switches associated with the lines, a plurality of connective link circuits having fixed terminals in said switches, an operator's equipment including a telephone, and an automatic switch associated individually therewith containing terminals of branches from the link circuits, whereby the operator's outfit may be associated with any link for purposes of connection, together with means to restore said operator's switch to normal or inactive position when each line connection has been established.

11. In a telephone exchange system, a plurality of subscribers' lines, primary selector switches associated with the lines, a plurality of connective link circuits having fixed terminals in said switches, an operator's equipment including a telephone, and an automatic switch associated individually therewith containing terminals of branches from the link circuits, whereby the operator's outfit may be associated with any link for purposes of connection, together with automatic means to restore said operator's switch to normal or inactive position when each line connection has been established.

In testimony whereof I affix my signature in presence of two witnesses.

EDWARD E. CLEMENT.
